US00D692871S

(12) **United States Design Patent**
Lee et al.

(10) **Patent No.:** US D692,871 S
(45) **Date of Patent:** ** Nov. 5, 2013

(54) **INPUT KEY FOR MOBILE
COMMUNICATION TERMINAL**

(75) Inventors: **Hyun-Do Lee**, Seoul (KR); **O-Chae Kwon**, Seoul (KR); **Il-Geun Bok**, Seoul (KR); **Seung-Ah Oh**, Seoul (KR)

(73) Assignee: **Samsung Electronics Co., Ltd.**, Suwon-Si (KR)

(**) Term: **14 Years**

(21) Appl. No.: **29/413,442**

(22) Filed: **Feb. 15, 2012**

(30) **Foreign Application Priority Data**

Oct. 5, 2011 (KR) 30-2011-0041131

(51) **LOC (9) Cl.** **14-03**

(57) **CLAIM**

The ornamental design for an input key for mobile communication terminal, as shown and described.

DESCRIPTION

FIG. 1 is a front perspective view of an input key for mobile communication terminal;

FIG. 2 is a front view of the input key for mobile communication terminal of FIG. 1;

FIG. 3 is a rear view of the input key for mobile communication terminal of FIG. 1;

FIG. 4 is a left-side view of the input key for mobile communication terminal of FIG. 1;

FIG. 5 is a right-side view of the input key for mobile communication terminal of FIG. 1;

FIG. 6 is a top plan view of the input key for mobile communication terminal of FIG. 1;

FIG. 7 is a bottom plan view of the input key for mobile communication terminal of FIG. 1;

FIG. 8 is a front view of the input key for mobile communication terminal of FIG. 1 shown in its environment; and,

FIG. 9 is an enlarged perspective view of the input key within dot-dash broken circle identified as "A" in the FIG. 8 view. The evenly spaced broken lines showing the remainder of the mobile communication terminal are directed to environment and are for illustrative purposes only; the broken lines form no part of the claimed design.

1 Claim, 9 Drawing Sheets
